UNITED STATES PATENT OFFICE.

HARRY HARDCastle, OF WELLINGTON, NEW ZEALAND.

TUNED CIRCUITS OF WIRELESS APPARATUS.

Application filed December 3, 1925, Serial No. 73,026, and in New Zealand November 5, 1925.

This invention relates to wireless apparatus of the type employing tuned oscillatory circuits, which in order to enable the apparatus to function correctly, requires to be tuned to one or more definite frequencies of electrical oscillation.

The tuning or adjustment of such circuits as before mentioned is a critical operation attended in a great many cases by objectionable results, and it is an object of this invention to provide improvements which will enable such tuning or adjustment to be carried out quickly, easily, and accurately, and without the objectionable results, mostly, or at least frequently associated with said tuning or adjusting operation.

The invention consists in placing in a tuned circuit of a wireless apparatus, a series of condensers each pre-tuned in conjunction with the inductance in the circuit, to a pre-determined frequency, any one of said condensers being capable by the use of a selector switch, of being actively incorporated in said tuned circuit, so as to tune or adjust the latter to a selected frequency.

This arrangement enables the circuit to be permanently provided with a number of different capacities any one of which can be instantly utilized to tune the circuit to a selected frequency, the frequencies available in the circuit being determined by the various capacities of the condensers placed therein.

In the drawings, Figure 1 illustrates diagrammatically one form of my invention, while Figure 2 illustrates diagrammatically a modified form.

In the diagram forming Figure 1 of the accompanying drawing 1, represents an inductance; 2, 2^a, 2^b, and 2^c, a series of condensers each pretuned in conjunction with the inductance 1 to a predetermined frequency; 3, a variable condenser; 4, a small series condenser for converting the variable condenser into a vernier control; 5 a switch point electrically connected with the variable condenser 3; 5^a, 5^b, 5^c, and 5^d, switch points electrically connected, each with one of the pretuned condensers 2, 2^a, 2^b and 2^c; 6, a selector switch; 7 the lead to the grid of a valve, or a crystal detector; and 8 the lead to earth.

The selector switch 6, may be connected to either the high potential or the earth potential sides of the condensers 2, 2^a, 2^b, 2^c, but

preferably it is connected to the high potential sides, and in the latter case the earth potential terminals of all the condensers 2, 2^a, 2^b, 2^c, may be joined together and the common connection 8 taken to some part of the apparatus at earth potential.

In such a group of pre-tuned condensers, the high potential terminals of the condensers are connected each to the separate switch point 5^a, 5^b, 5^c, 5^d, the selector switch 6 being mounted so as to be capable of being moved across said points, to contact with any selected one thereof, and place the condenser electrically connected with the selected point, actively in the circuit.

When more than one tuned circuit each as before described is being utilized (see Figure 2) the selector switches 6 can be mounted on a single device 9, operated by a single control handle 10, or said switches 6, may be separately placed and connected together by any convenient mechanical means which will enable them to be operated from a single control or as one unit.

Also in the last described arrangement, flexible or equivalent connections 11 are used between the switches 6 and the tuners.

The condensers employed can be of any suitable type sufficiently small to enable them to be incorporated in the required numbers and fitted with means for adjusting their capacities and having the character of permanence of adjustment.

In order to compensate for small variations from accurate tuning, vernier condensers may be associated with each circuit.

When series of condensers arranged and adapted to be utilized as aforesaid, are used in conjunction with continuously variable condensers, the earth potential sides of the latter can be connected to the earth potential sides of the other condensers and the high potential sides of the variable condensers 6 to switch points 5 so that the selector switch 6 can be made to cut out the pre-tuned condensers 2, 2^a, 2^b, 2^c, and switch in the variable condensers 3.

Also when a continuously variable condenser is used in conjunction with pre-tuned condensers, the former may be utilized as a vernier control for the pre-tuned condensers by placing a small condenser 4 in series with the variable condenser between the high potential side of the latter, and the selector switch 6, whereby the variable condenser

will have its effective capacity reduced to a value controlled by the capacity of the small condenser 4.

5 The apparatus described may be associated with means controlled by the same switch control, for introducing additional or alternative inductances, to extend the frequency range of the apparatus.

What I do claim and desire to obtain by
10 Letters Patent of the United States of America, is:—

In a radio-frequency apparatus comprising a variable condenser of ordinary type in an oscillatory circuit, the combination with such
15 condenser of a group of fixed condensers and

a switching system by which any of the condensers in the group can be substituted for the ordinary variable condenser in circuit to tune the circuit to a frequency determined by the setting of the condenser so connected, and in association with said usual variable condenser, a series condenser so connected that it and said usual condenser remain connected in parallel with each of the condensers functioning in place of the usual condenser, the latter condenser being then available as a fine adjusting device.

In testimony whereof I have signed my name to this specification.

HARRY HARDCASTLE.
